UNITED STATES PATENT OFFICE.

ROBERT C. GLASSCO, OF ANDERSON, INDIANA, ASSIGNOR OF TWO-THIRDS TO COMPUTING CHEESE CUTTER COMPANY, OF ANDERSON, INDIANA, A CORPORATION.

PARING DEVICE.

1,373,882.

Specification of Letters Patent. Patented Apr. 5, 1921.

Application filed December 23, 1919. Serial No. 346,857.

To all whom it may concern:

Be it known that I, ROBERT C. GLASSCO, a citizen of the United States, and a resident of Anderson, county of Madison, and State of Indiana, have invented a certain new and useful Paring Device; and I do hereby declare that the following is a full, clear, and exact description thereof, reference being had to the accompanying drawings, in which like numerals refer to like parts.

This invention relates to a vegetable peeler or parer, especially adapted for potatoes and the like, and formed from a flat strip of sheet metal.

One feature of the invention is the plurality of angularly protruding knives stamped from the metal and slightly spaced therefrom to the extent of the thickness of the peeling, so as not to dig far enough into the vegetable to be wasteful, and the slots of sufficient size to permit the peelings to readily pass through the body of the peeler.

Another feature of the invention lies in the provision of an eye removing portion, which also serves for a thumb or finger piece, which may be utilized for digging into rotten portions and removing the eyes of potatoes. By means of this device the potato or similar vegetable may be rapidly peeled by simply scraping the peeling from the surface thereof by holding it between the fingers.

The full nature of the invention will be understood from the accompanying drawings and the following description and claims.

In the drawings, which are made a part of this application, Figure 1 is a plan view of the novel and improved paring device looking at the knives thereof. Fig. 2 is an end elevation of the same. Fig. 3 is a side elevation of the paring device and shows a combined eye remover and finger or thumb piece. Fig. 4 is an enlarged detailed view showing the slots and knife blanks. Fig. 5 is a sectional view taken on the line 5—5 of Fig. 4 and shows the manner in which the knife blanks are positioned with respect to the parer and the way the blanks are sharpened to form the knife blades.

In the drawings 10 indicates a flat plate body portion from which the improved paring device is formed. To those skilled in the art it will be understood that the blank

for forming the paring device may be cut from a long strip of sheet metal. The blanks so cut are then slotted in any suitable manner, as illustrated in Fig. 4. Herein the slots 11 are shown in staggered relation and each slot is preferably channel shaped, so that the knife blanks 12 are formed with parallel knife edges 13. The slots as shown are suitably spaced apart and in rows, each alternate row having its slots opposite the body portion space between adjacent slots in the adjacent rows. By thus arranging the slots, the knife blanks will remove the peeling from the vegetable or the like without leaving any strips of peeling upon the vegetable. Although the slots are shown channel shaped, the same may be otherwise formed, such as an open triangle. The channel shape, however, is preferred because of the strength imparted to the portion between the knife blank and the plate portion.

The plate portion is slotted, as shown in Fig. 3, with a U shaped slot 14. The plate portion included between the sides of said U shaped slot projects outwardly from said plate 10 and forms an eye remover 15 with a rounded knife edge 16. This round pointed projecting knife portion may also be used to remove bruised specks and the like, and in addition thereto, may be used for a finger or thumb-rest and support when the paring device is grasped.

The edges of the plate portion 10 are bent upwardly to form grip handles or grasping portions 17. The upper and outer edges of said grasping portions are bent, as shown in Fig. 2, to form a beaded edge 18, so that the fingers may readily engage said grasping portion and securely grip the same without being cut by a sharp edge. As shown in Figs. 2 and 3, the eye remover and thumb piece 15 extends outwardly from said plate 10, while the grasping edge 17 extends upwardly therefrom and is provided with an outwardly turned bead 18. When the thumb or finger is placed upon the projection 15, the paring device is firmly gripped between the yielding grasping end 17 and the bead 18, and is also held in position by the finger or thumb resting against the edges of the U shaped slot 14. The finger or thumb presses into said slot and in this manner, the paring device may be more

firmly gripped. If desired, a similar projection 15 may be formed on the opposite edge, although the same is not necessary.

As shown in Figs. 2 and 5, the knife blanks 12 extend downwardly from said plate portion and may be bent in that position in any suitable manner. When bent, as shown, the upper face 19 of said blank portion 12 provides an inclined slide upon 10 which the paring removed by the knife is carried upwardly and away from the same. The knife edges 13 are herein shown sharpened in any suitable manner, the blanks preferably having their outer edges removed so 15 that the cutting face 20 is formed, which is substantially parallel to the plate portion 10. It will be obvious to those skilled in the art that the knife blanks may be otherwise downwardly bent or may be otherwise 20 sharpened. However, the preferred construction is as shown, since the edges of the paring knives may be re-sharpened readily by engaging the paring device upon a suitable sharpening or grinding surface. In 25 this manner the novel and improved paring device may be re-sharpened until the knives have been substantially sharpened away.

From the foregoing description of the individual blades described in the formation 30 of the novel and improved paring device, it will be understood that the device may be formed by these operations, to-wit: Cutting the blank from a strip of sheet metal, said blank remaining in the punch press in which 35 it is simultaneously slotted with channel shaped slots and with a U shaped slot, continued movement of said press will bend upwardly the grasping ends or edges of said plate and simultaneously therewith the knife 40 blanks are bent and inclined to said plate and the final stage of the movement, said press will crimp and form the bead upon the upper edge of the grasping ends. The 45 formed blank is then removed from the press, held to a suitable grinding surface which sharpens the knife edges and forms the same as described substantially parallel to the plate portion from which the same was punched. The essential steps in the 50 operation are the punching, bending and sharpening, and by this means and in this manner, the novel and improved paring device is formed, as shown.

The invention claimed is:

55 1. In a paring device, the combination of

a plate provided with a hand engageable end extending angularly of the plate and a lug formed from the angularly extending end and extending angularly of said end to form a finger support. 60

2. In a paring device, the combination of a plate portion provided with oppositely positioned hand engageable ends extending angularly of the plate, and paring means between said ends, and a finger supporting lug 65 extending angularly of one of said ends and formed from the same.

3. In a paring device, the combination of a plate provided with paring means and a hand engageable end extending angularly of 70 the plate, and a finger supporting lug formed from the angularly extending end and lying substantially parallel to said plate.

4. In a paring device, the combination of a plate provided with paring means and a 75 hand engageable end extending angularly of the plate, and a finger supporting lug formed from the angularly extending end and lying in substantially the same plane with said plate. 80

5. In a paring device, the combination of a plate provided with oppositely positioned hand engageable ends extending angularly of the plate and positioned upon the same side thereof, paring means between said 85 ends and positioned upon the opposite side of said plate, each of said angularly extending ends upon its free edge being provided with an outwardly turned edge to form a gripping portion upon each of said angularly extending ends, whereby the paring 90 device may be grasped in one hand.

6. In a paring device, the combination of a plate provided with oppositely positioned hand engageable ends extending angularly 95 of the plate and positioned upon the same side thereof, paring means between said ends and positioned upon the opposite side of said plate, each of said angularly extending ends upon its free edge being provided 100 with an outwardly turned edge to form a gripping portion upon each of said angularly extending ends, whereby the paring device may be grasped in one hand, and a finger supporting lug extending angularly 105 of one of said ends and formed from the same.

In witness whereof, I have hereunto affixed my signature.

ROBERT C. GLASSCO
